UNITED STATES PATENT OFFICE.

JOHN AUDLEY COUPER, OF MARIETTA, GEORGIA.

SWIMMING-SHOE.

SPECIFICATION forming part of Letters Patent No. 320,762, dated June 23, 1885.

Application filed March 23, 1885. (No model.)

To all whom it may concern:

Be it known that I, JOHN A. COUPER, of Marietta, Cobb county, Georgia, have invented a new and Improved Swimming-Shoe, of 5 which the following is a full, clear, and exact description.

The object of my invention is to provide a new and improved shoe to be attached to the foot to assist a person in swimming.

10 The invention consists in the combination, with a foot-plate, of wings pivoted on the under side of the same and of straps for holding the plate on the foot.

Reference is to be had to the accompanying 15 drawings, forming part of this specification, in which similar letters of reference indicate corresponding parts in all the figures.

Figure 1 is a side view of my improved swimming-shoe. Fig. 2 is a rear view of the 20 same, the wings being separated. Fig. 3 is a rear view of the same, the wings being swung together; and Fig. 4 is a rear view of the shoe, the wings being detached.

The foot-plate A is provided with the front 25 strap, B, the heel-strap C, and heel-plate D, in the same manner as a roller-skate, and from the bottom of the foot-plate two or more apertured lugs, E, project, through which a rod or shaft, F, is passed, on which two wings, G, 30 are hung by metal or leather loops H. The upper edges of the wings G are beveled, as

shown in Figs. 3 and 4, so as to adapt them to swing together.

A spring-catch, J, is secured on the rear end of the rod F, and engages with the rear 35 lug E, and thus locks the rod in place.

The foot-plate is held on the bare foot by means of the straps C D.

When the person strikes out, the wings G are swung from each other and offer much 40 resistance, and when the foot is pulled forward the wings swing together, as shown in Fig. 3, and offer very little resistance.

When the person wishes to walk on land, the spring-catch J is disengaged from the lug 45 E, and the rod F is pulled out to release the wings.

The wings may be made of wood, sheet metal, or other material.

Having thus described my invention, I claim 50 as new and desire to secure by Letters Patent—

The combination, with a foot-plate, of apertured lugs projecting from the bottom of the same, a shaft or rod held on the lugs, wings hung on the rod, and a spring-catch for 55 locking the rod in place in the lugs, substantially as herein shown and described.

JOHN AUDLEY COUPER.
